UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

DESIGN FOR A TOY CONSTRUCTION ELEMENT.

Application filed December 8, 1921. Serial No. 521,044. Term of patent 14 years.

To all whom it may concern:

Be it known that I, ALFRED C. GILBERT, a citizen of the United States, residing in New Haven, New Haven County, Connecticut, have invented a new, original, and ornamental Design for a Toy Construction Element, of which the following is a specification when taken in connection with the accompanying drawings, of which—

Fig. 1 is a perspective view of a toy con-

struction element showing my new design; Fig. 2 is a front elevational view of the same; and

Fig. 3 is a side elevation of the construction element.

I claim:

The ornamental design for a toy construction element, substantially as shown.

ALFRED C. GILBERT.
